UNITED STATES PATENT OFFICE.

JOHN ALSTON MOORHEAD, OF SHARPSBURG, AND JOHN PATTERSON, OF PITTSBURG, PENNSYLVANIA.

RAIL-FASTENING.

1,001,879.

Specification of Letters Patent. Patented Aug. 29, 1911.

Application filed September 17, 1910. Serial No. 582,461.

To all whom it may concern:

Be it known that we, JOHN A. MOORHEAD, a resident of Sharpsburg, in the county of Allegheny and State of Pennsylvania, and 5 JOHN PATTERSON, a resident of Pittsburgh, county of Allegheny, and State of Pennsylvania, have invented a new and useful Improvement in Rail-Fastenings; and we do hereby declare the following to be a full, 10 clear, and exact description thereof:

Our invention relates to rail fastenings and particularly to a tie plate or chair construction for holding railroad rails to metallic ties. Its principal object is to provide 15 an improved metallic tie plate of simple construction which will effectively hold the rail in place on the metallic tie employed, and at the same time take all side thrust of the rail off the bolts and thereby prevent shearing 20 of the same and the serious accidents caused by such shearing.

A further object is to provide an improved insulating device and a conducting connection to carry the current used in rail-way signaling between the rails.

To these ends our invention consists, generally stated, in the combination with a tie plate having a plurality of lugs (preferably rectangular) on its under surface on each 30 side of the rail base, and provided with transverse flanges adapted to receive and bear against the rail base, of a metallic tie provided with an upper horizontal flange or face, having a plurality of slots with 35 which said lugs exactly register. The metallic tie employed is preferably of the ordinary I-beam type, although it will be understood that any type of tie which has slots in its upper surface adapted to fit the lugs 40 on the lower face of the tie plate is within the spirit of our invention. The lugs and the slots are preferably rectangular so that the tie plate is held securely against movement on the tie in any horizontal direction, 45 as distinguished from sloping or angular slots which necessitate the holding of the tie plate in position by means of bolts. By our invention all side or end thrust is taken off the bolts and they merely serve to hold 50 the tie plate down to the tie and prevent its loosening by vibration during traffic over it.

Our invention also consists in an improved insulating device comprising princi-

pally an insulation plate and one or more metallic protecting and conducting plates 55 for preserving the same and carrying the electric current where the device is used at a rail joint.

In the accompanying drawings illustrating our invention, Figure 1 is a perspective view partly in vertical section and partly broken away of a complete rail fastening. Fig. 2 is a perspective detail view illustrating the metallic tie employed in Fig. 1. Fig. 3 is a like view illustrating a modified 65 form of the plate. Fig. 4 is a side view partly in vertical section illustrating a rail joint connection embodying our invention. Fig. 5 is a perspective detail view, upside down, of the protecting metallic basket or 70 pillow plate preferably employed. Fig. 6 is a perspective view illustrating a modification; and Fig. 7 is a detail sectional view illustrating the construction of bolt washer employed.

75

The rail 1 fits within the transverse flanges 2 of the tie plate 3. The tie plate 3 is provided on its under surface with the depending rectangular lugs 4, two or more of which are preferably arranged on each 80 side of the rail base 5. The lugs 4 fit within the rectangular slots 6 in the upper face or flange 7 of the metallic tie 8, which is illustrated as a tie of the I-beam type.

The bolt holes 13 are arranged inside of 85 the slots 6 in the tie 8, but outside of the rail base 5, so that the bolts 14 do not abut against the said rail base. Any convenient number of such bolts 14 may be employed, two being illustrated in Fig. 1 and four bolt 90 holes being shown in Fig. 2. The bolts 14 are each provided with a nut 15 bearing on a washer 10 which fits over the rail base 5. The tie plate 3 is thus securely held to the tie 8 and the rail 5 is held down within its seat 95 16 between the flanges 2. The tie plate 3 is also preferably provided with the exterior flanges 9, arranged outside of the flanges 2 abutting against the rail base and adapted to carry the washers 10 in connection with 100 the said flanges 2. The washers 10 are provided with the annular portions 11 of fiber or other insulating material so that there is no metallic contact between the rail base 5 and the said washers.

105

In order to provide complete insulation be-

ween the rail 1 and the tie plate 3, we further provide the insulating plate or basket 17 within the seat 16 carrying the rail base. Said plate 17 is constructed of any suitable insulating material and has the vertical flanges 18 which are arranged along its sides to extend substantially the height of the tie plate flanges 2. By this means short-circuiting of the signal-current across the metallic ties is effectually prevented. We also prefer to employ in connection with the insulating plate 17 the metallic protecting plate 20 within the insulating plate 17 and fitting against the bottom 21 of the rail base 5, it having the side flanges 22 extending upwardly within the flanges 18. The protecting plate 20 serves as an electrical conductor or bond to carry the signal current employed in railroads between the rails. Thus, in Fig. 4 we have illustrated the junction 25 of the rails 26 and 27, connected by the ordinary rail joint or fish plate 28. The member 29 illustrated in Fig. 4 is of a form similar to the tie 8 although it will be understood that this member also represents a rail brace of any construction employed where the joint is not on the tie but between the ties.

The protecting plate henceforth termed the bond plate 20 is also preferably provided with the depending flanges 30 where it is employed in connection with the rail fastening illustrated in Fig. 1, the flanges 30 registering over the like flanges 31 of the insulating plate 17 and serving to prevent the dis- placement on the tie of the said insulating plate and the bond plate 20. Fig. 3 illustrates the tie plate 3 with the roughened top face 54 which aids in holding the bond plate 20 in position, or in preventing rail slipping where such bond plate is not employed, as in street railways or the like, the bottom face 3" being also preferably roughened to aid in gripping the tie. In this connection, we prefer to employ also the supplementary basket plate 33 which carries within it the insulating plate 17 and the bond plate 20 as illustrated in Fig. 1. The vertical flanges 34 of the basket plate 33 together with the depending flanges 35 serve to incase the insulating plate 17 and to protect it against surface wear and grinding from the tie plate 3. The basket plate 33 is in all respects similar in shape to the insulating plate 17, and the bond plate 20, and we thus provide a perfect protection for the insulating plate 17, and in connection with the insulated washer 10 a complete insulation between the rail and tie plate. The basket plate 33 is preferably provided with the roughened or milled surface 33' on its bottom and also if desired its top face, as illustrated in Fig. 5, to prevent endwise slipping of the rail and also aid by friction the means for retaining the rail against side thrust, especially where

the tie employed has a roughened surface. 65 Where also the rail joint is on top of the tie or the basket construction of our invention is employed between ties the bond plate 20 serves as an electrical conductor between the rail ends. 70

In Fig. 6, we have illustrated a modification in which the basket plate 40 is of heavier construction and serves also as a tie plate, although the side thrust of the rails is here taken by the bolts 41 through the ends 42 provided with the clips 43, which fit over the rail base 44. The insulating plate 45 is similar to the plate 17 above described and the bond plate 46 is similar to the plate 20 each of said plates 40, 45, and 46 being provided with the vertical longitudinal flanges 40', 45' and 46', respectively, and having the transverse depending flanges 40", 45" and 46", as shown in Fig. 6. The clip 43 has the lower face of insulating material so that complete insulation is provided around the rail base 44. 80

In Fig. 3 the modified form of plate 50 illustrated has depending lugs 51 situated as in Fig. 1, but connected by transverse flanges 52 for bracing the same. The slots 53 lighten the plate and the roughened surface 54 aids in gripping the rail base. 85

The main features of our invention consist, however, in providing a tie plate of simple 95 construction which can be conveniently manufactured by a single rolling and shearing operation and which serves in connection with the tie to take all side thrusts off the bolts employed. This is accomplished without the necessity of bending any flanges or clips over the rail base and dispenses entirely with this and other complicated expedients hitherto employed. The rectangular lugs and slots each serve to provide a 100 double abutting or shearing surface, and thereby great resistance to side thrusts of the rail. 105

What we claim is:

1. In a rail fastening the combination with 110 a rail and a metallic tie supporting the same and having its upper face provided with a plurality of slots situated on opposite sides of the rail base, of a tie plate provided with means for engaging the rail base and preventing lateral movement thereof and having a plurality of depending lugs in exact register with said slots and fitting within the same. 115

2. In a rail fastening, the combination 120 with a tie plate adapted to receive and hold the rail and having a plurality of depending lugs on each side of the rail base, of a tie having a plurality of slots adapted to fittingly register with said lugs and thereby 125 hold the tie plate against horizontal movement.

3. In a rail fastening, the combination

- with a tie plate adapted to receive and hold the rail and having a plurality of depending lugs, of a tie having a plurality of slots adapted to register with said lugs and there-
 5 by hold the tie plate against horizontal movement, bolt holes in said tie plate and bolts arranged outside of the rail base but adapted to hold the rail downwardly to the tie.
- 10 4. In a rail fastening, the combination with a rail of a tie plate having vertical flanges on each side of the rail base and provided with depending rectangular lugs arranged outside of the rail base and a tie
 15 provided with rectangular slots adapted to receive and fit said lugs, and bolts arranged outside of said flanges and adapted to fasten said lugs in said slots and said rail to said tie plate.
- 20 5. In a rail fastening, the combination with a rail of a tie provided with a plurality of rectangular slots, a tie plate having a plurality of rectangular lugs on opposite sides of the rail base in register with
 25 said slots and provided with vertical longitudinal flanges along the rail base on each side thereof and supplementary flanges outside of said vertical flanges, bolt holes through said tie plate, and between said
 30 supplementary flanges and said vertical flanges, bolts extending therethrough and washers carried by said bolts and extending over the rail base to hold the same downwardly.
- 35 6. In a rail fastening, the combination with a rail and a metallic tie of a tie plate provided with means for holding it against side thrusts on the tie and having vertical flanges abutting against the rail base, supplementary flanges outside of said vertical flanges and bolts extending through said tie plate and tie and provided with washers carried on said vertical and supplementary flanges, respectively, and extending over the rail base.
- 40 7. In a rail fastening, the combination with a rail of a metallic tie having its upper face provided with a plurality of slots and suitable bolt holes, and a tie plate provided with flanges abutting against the rail base and depending lugs adapted to register with said slots and bolts arranged outside of said flanges and provided with means for holding the rail to the tie by pressure on the rail base.
- 45 8. In a rail fastening, the combination with a rail of a metallic tie provided in its upper face with a plurality of slots, a tie plate having a plurality of depending lugs in register with said slots and provided with vertically extending flanges on each side of the rail base, bolts connecting said tie plate and tie and arranged outside of said flanges
 50 and provided with insulating means for holding said rail base down, and a plate of insulating material provided with flanges internally fitting said vertical flanges and adapted to provide complete insulation between the rail and tie plate.
 55 9. In a rail fastening, the combination with a rail of a metallic tie provided in its upper face with a plurality of slots, of a tie plate having a plurality of depending lugs in register with said slots and vertically extending flanges on each side of the rail base, supplementary flanges outside of said vertical flanges, bolts extending through said tie plate and tie between said supplementary and vertical flanges, washers on said bolts provided with faces of insulating material in contact with the rail base and a plate of insulating material separating the rail base from said tie plate including its vertical flanges.
 60 10. In a rail fastening, the combination with a rail and a metallic tie, of a tie plate provided with means for holding it to the tie and having on its upper face vertically extending flanges on each side of the rail base and a plate of insulating material between the rail base and tie plate and having vertically extending flanges arranged between said vertical flanges on said tie plate and the edges of the rail base, and depending flanges fitting the tie and adapted to hold said plate against movement thereon.
 65 11. In a rail fastening, the combination with a rail of a metallic tie, a tie plate provided with means for holding it thereon and having vertically extending flanges on each side of the rail base, a plate of insulating material separating the rail base from said tie plate including its flanges and a protecting plate of metallic material arranged between said insulating plate and said tie plate, respectively.
 70 12. In a rail fastening, the combination with a rail and a metallic tie, of a tie plate fastened thereto and provided with means for holding the rail against sidewise displacement, a plate of insulating material separating said tie plate and rail and metallic plates containing said insulating plate and arranged to contact with the rail base and said holding means, respectively, and thereby protect said insulating plate from wear.
 75 13. In a rail fastening, the combination with a rail of a metallic tie, a tie plate fastened thereto, a plate of insulating material between said rail and tie plate, said tie plate having vertically arranged flanges along the rail base and said insulating plate having like flanges within said vertical flanges and depending flanges in register with the sides of the metallic tie, a protecting metallic plate or basket provided with

vertical flanges separating the like flanges of said insulating plate and said tie plate and with depending flanges separating said depending flanges on said insulating plate and said tie.

14. In a rail fastening, the combination with a rail and a metallic tie, of a tie plate provided with means for fastening to said tie and for holding said rail against lateral displacement, a plate of insulating material separating said rail and tie plate at all points, and protecting plates of metallic material arranged on each side of said insulating plate and in contact with said rail and tie plate respectively.

15. In a rail fastening, the combination with a rail and tie, of a tie plate provided with holding means to prevent lateral displacement of the rail on the tie, and a plate of insulating material arranged between said rail and tie plate and provided with

depending flanges fitting over said tie plate to prevent its longitudinal displacement thereon.

16. In a rail fastening, the combination with a rail and a metallic tie, of a tie plate provided with means for fastening to said tie and for holding said rail against lateral displacement thereon, a plate of insulating material and a protecting plate of metallic material arranged between said rail and tie plate and each provided with a depending end flange fitting over said tie plate, substantially as described.

In testimony whereof, we the said JOHN A. MOORHEAD and JOHN PATTERSON, have hereunto set our hands.

JOHN ALSTON MOORHEAD.
JOHN PATTERSON.
